UNITED STATES PATENT OFFICE.

TERANCE SCULLIN, OF CLEVELAND, OHIO.

DESIGN FOR A RECESS SASH-LIFT.

43,727.

Specification for Design.

Patented Mar. 18, 1913.

Application filed November 29, 1912. Serial No. 734,204. Term of patent 14 years.

To all whom it may concern:

Be it known that I, TERANCE SCULLIN, a citizen of the United States, and residing at Cleveland, in the county of Cuyahoga and State of Ohio, have invented a new, original, and ornamental Design for a Recess Sash-Lift, of which the following is a specification, reference being had to the accompanying drawings, forming part thereof.

Figure 1 of the drawing represents a front

view of the said design, and Fig. 2 a cross section through the center thereof.

I claim:

The ornamental design for a recess sash lift, as shown.

TERANCE SCULLIN.

Witnesses:

F. B. GUINAN,
MARGARET DOWLING.
